MULTIPLEX TRANSMISSION

Richard Howland Ranger, Newark, N. J., assignor
to Radio Corporation of America, a corporation
of Delaware

Application January 5, 1933, Serial No. 650,215

7 Claims. (Cl. 250—9)

The present invention relates to a multiplex communication system and is, in general, directed to a system by which a plurality of messages may simultaneously be transmitted from a single transmitting instrumentality without causing the so-called "cross talk" or interference between each message transmitted.

Briefly, the invention comprises a system by which it is possible to transmit, for example, two telegraphic signals and one sound signal simultaneously, or for example, two sound signals and one telegraphic signal simultaneously, or else to transmit three sound or three telegraphic signals simultaneously.

In its broadest form the invention comprises ways and means by which a predetermined tone carrier frequency is generated and is then modulated by a second generated tone frequency so as to produce therefrom upper and lower side band frequencies. The side band frequencies according to one form of the invention may then be keyed by way of telegraphic signals and one of the generated tone carrier frequencies may then be modulated by the sound transmitted. In each case the two locally generated tone frequencies are generated by way of oscillators which are extremely stable and substantially not subject to shift in frequency. The output from all of the keyed or modulated frequencies is then combined in a combining unit to which a carrier frequency is supplied but suitably suppressed and, then, through the use of linear amplifiers tuned to a predetermined frequency relative to one of the side band frequencies produced the various signals may be transmitted.

According to a preferred form for keying both the sound and telegraphic signals I have herein shown and described a system by which the sound and keying or telegraphic signals may be keyed by way of a plate circuit keying scheme. To receive the signals transmitted it is preferable to provide three distinct receiving units in order that there will be no interference between the various transmitted signals, although it is possible to use only a single receiving instrumentality provided with suitably arranged filtering systems or to provide two separate receivers, one being for the sound signals and the other for telegraphic signals.

With the above stated general features of the invention having been pointed out it will be appreciated that the invention has as one of its primary objects that of providing a transmission system for simultaneously transmitting a plural-

ity of signals without causing interference between the various transmitted signals.

A further object of the invention is to provide a system for transmitting a plurality of signals which may consist of either sound signals, telegraphic signals, or a combination of both, and at the same time avoid all interference between the various transmitted signals.

Still a further object of the invention is to provide a simplified multiplex transmission system in which it is possible to transmit simultaneously a plurality of chosen and selected signals of different characteristics without any possibility of so-called "cross talk" between channels.

Further objects of the invention are, of course, to provide a system for multiplex transmission which is simpler than those heretofore suggested; to provide a transmitting system for multiplex which can be installed conveniently in connection with existing types of radio or wire line transmission systems; and to provide a multiplex transmitting system which is extremely efficient in its use.

One of the main objects and advantages of the present arrangement is that all channels in the system are absolutely locked as regards both frequency and phase. This absolutely prevents different signals from "sliding" or moving in or out of the frequency band to which the receiver filters are selective, that is, the filter for any one signal in particular or the filter for any other signal. In this manner no signal can reach any other filter than the one which is supposed to distinguish the particular signal. In this manner the voice and/or telegraph signals and/or light signals cannot interfere one with the other.

Other and further objects and advantages of the invention will become apparent and at once suggest themselves to those skilled in the art to which the present invention relates by reason of the following specification and claims in connection with the accompanying drawings in which:

Fig. 1 illustrates one suitable form of transmitter circuit arrangement; and

Fig. 2 illustrates one of several suitable forms of apparatus for receiving the signals transmitted from the transmitting arrangement of Fig. 1.

To make reference now to the accompanying drawings it will be seen that the transmitter system combines several different unitary structures in the form of oscillators 1 and 2 for generating the tone frequencies or carriers of intermediate frequency, a combining unit 3 for the output frequencies of both tone generators, a sound modu-

lation system 4, telegraphic or picture signal modulation systems 5 and 6, a combining unit 7 for the carrier frequency oscillator 8, having its frequency doubled in a plurality of carrier frequency doubling stages 9 and 10 located intermediate between the carrier frequency generator 8 and the combining unit 7, whose output is amplified in a plurality of linear amplifying stages 12 and 13 and then transmitted by way of 10 a transmitting device 14.

To refer now more specifically to the particular circuit arrangement which has herein been shown and described as illustrating one form of system to practice the invention, it is seen that one tone or carrier frequency of intermediate value, which for convenience of illustration may herein be assumed to be a 3 kc. tone, is generated in the oscillation generator tube 21 having connected with its output electrode a resonant circuit 23 comprising inductance 25 and capacity 27. The output electrode of the tube 21 is energized by way of a potential source 28 shunted by a variable capacity element 29 and across the input circuit is a piezo electric crystal control 31 shunted by the resistor element 33. The generated frequencies from the oscillator 21 appearing in the tank or resonant circuit 23 are then transferred to the secondary 37 of the transformer comprising the inductance 25 of the plate circuit and the winding 37 to be supplied to the input electrode of an amplifier 35, from the output of which they are transferred to be impressed upon the input electrodes of a pair of push-pull connected amplifier tubes 57 and 59.

Simultaneously with the generation of a low frequency tone carrier by the oscillation generator 21 a higher frequency tone or intermediate frequency carrier, herein assumed to be 100 kc., is generated in the oscillator 39 having connected with its plate electrode a tank circuit 41 comprising an inductance element 43 forming the primary of a transformer and a capacity element 45. Similarly to the oscillator 21 the frequency generated and appearing in the tank circuit 41 is controlled by way of a crystal control 51, which crystal 51 is shunted by a resistor element 53. The generated oscillations from the tank circuit 41 appear in the inductance 43 constituting the primary of a transformer and are then transferred to a plurality of secondary coils or windings 55 and 193. From the winding 55 the generated signals of fixed frequency are supplied to the push-pull amplifier stage comprising the tubes 57 and 59 having the grid electrodes thereof suitably biased by way of a biasing source 61 and having the plate electrodes energized from a common plate potential source 62.

The generated frequency of the oscillator 39 is supplied to the push-pull stage comprising tubes 57 and 59 by way of a carrier suppression modulator system so that in the output circuit of the tubes 57 and 59, formed as the primary winding 63 of the transformer 63, 65, there appears frequencies of 97 kc. for example and 103 kc., for example, which correspond to the upper and lower side bands formed by beating a 100 kc. generated frequency from the oscillator 39 with the 3 kc. generated frequency from the oscillator 21.

If now it is desired to produce a plurality of telegraphic signals or, for example, picture controlled signals, these signals may be impressed at the signal inputs generally designated "A" and "B" and supplied across a series of terminals 67, 69 and 71, 73, respectively. The signals supplied in the channel "A" across the terminals

67, 69 are then impressed upon the input electrode of a vacuum tube amplifier 75 across a resistor element 77. The input electrode of the tube 75 is normally biased positively by way of a biasing source 78 so that in the absence of signals across the terminals 67, 69 plate current which is supplied by way of a plate supply source 79 to the tube 75 will flow and thus produce a substantial voltage drop across the resistor 81 which produces a change in potential at 10 the point of connection of the conductor 83 with the potential source 79 and the resistor 81 to carry this point more negative and thus change the effective biasing voltage supplied by the biasing battery 85 through the conductor 81 to the 15 push-pull connected amplifier tubes 89 and 90 so as to prevent the tubes 89 and 90 from passing current supplied thereto from the oscillator tube 91 comprising the usual electrode elements 92, 93 and 94.

The oscillator 91 is not inherently stable but is of the general type known as the Hartley oscillator and comprises the split plate coil 95 to the midpoint of which the cathode electrode of the vacuum tube 91 is connected and which split plate 25 coil 95 is shunted by a variable capacity 97. Energy is supplied to the plate circuit of the oscillator 91 from a plate potential source 98 and the frequency generated in the oscillator, which may herein be assumed to be substantially of the 30 order of 103 kc., which is the resonant frequency of the tuned circuit comprising the inductance 95 and the variable capacity 97 is then adapted to be "locked" by one of the side band frequencies generated as a beat frequency produced by modulating the 100 kc. tone, assumed to be generated by the oscillator 39, by the 3 kc. tone, assumed to be generated by the oscillator 21, which beat frequency appears in the transformer output 63 of the push-pull stage comprising vacuum tubes 40 57 and 59.

The frequencies corresponding to the upper and lower side bands, assumed to be 97 to 103 kc., are transferred from the primary 63 to the secondary winding 65 from which they are conveyed 45 by way of the conductor 99 through a winding 100 and thence through the conductor 101 through a winding 102 and conductor 103 back to the transformer secondary 65. The frequencies flowing through the winding 102 which are 50 adapted to be impressed by way of the coupling existing between the winding 102 and the inductance 95 of the oscillator circuit serve to lock the oscillator 91 at its normally generated frequency so that the energy transferred to the 55 secondary winding 104 of the transformer comprising the inductance 95 of the oscillator 91 and the winding 104 is then impressed upon the input circuit of an amplifier 105 whose output 60 is connected to the push-pull stage comprising tubes 89 and 90 through the transformer formed from the windings 106 and 107.

If now signals are impressed upon the signal input stage "A" and across the terminals 67 and 69 so that the signal applied at terminal 67 is negative and the signal applied at terminal 69 is positive it can be seen that the grid electrode of the tube 75 will be carried negative to a point sufficient to cut-off the plate current flowing in the output circuit of the tube. Then, by virtue of the increase in the effective voltage acting upon the grids of the push-pull tubes 89 and 90, current flows in the output circuit of the push-pull stage.

Assuming now that the oscillator 91 is gen-

erating a frequency of 103 kc. and that this frequency is stabilized by the 103 kc. tone or intermediate frequency appearing in the winding 102 there will appear then in the output circuit comprising the transformer 109, to which plate voltage for the amplifiers 89 and 90 is supplied from a source 108, the 103 kc. tone frequency interrupted at a rate corresponding to the rate of keying picture or telegraphic signals at the signal input "A". These signals are then transferred through a transformer secondary 113 to vacuum tube amplifier 127 whose plate circuit includes the plate potential source 129 and the transformer primary 131.

15 Similarly, the oscillator system comprising the oscillator tube 135 having plate, grid and filament electrodes 137, 139 and 141 of which the plate electrode is energized from a plate voltage source 143, produces in the oscillatory circuit comprising 20 the split plate coil 145 shunted by the capacity 147, oscillation frequencies at 97 kc., for example. This oscillator is likewise locked in step by the beat frequency signals of 103 kc. and 97 kc., of which the latter is effective on the oscillator 135, 25 appearing in the winding 160 connected with the secondary winding 65 of the transformer 63, 65 so that the frequency of the oscillator 135 is now stabilized at 97 kc. by the constant frequency generated in the oscillators 1 and 2. This 97 kc. 30 frequency is then impressed by way of the pickup coil 148 upon the input electrode of the vacuum tube amplifier 151 which has connected in its plate circuit the primary winding 155 of the transformer 155, 157 having its secondary connected to the input electrodes of the push-pull tubes 177 and 179. The signals from the second channel "B" which are to be transmitted simultaneously with the signals from the first channel "A" are now impressed across the terminals 71, 40 73 so that a negative signal is supplied to the terminal 71 and a positive signal is applied to the terminal 73 across the resistor 163. It is apparent that this negative signal acting on the grid of tube 165 is so great, as was explained in connection with channel "A", that it overcomes completely the positive bias supplied to the input electrode of the tube 165 from the battery 167 and thus interrupts the plate current which has previously flowed through the tube through the 45 plate voltage supply source 169 and to ground through the resistor 171.

45 The potential at the point of connection of the conductor 173 with the negative terminal of the battery 169 and the upper end of resistor 171 is raised with a decrease in plate current in this tube 165 and the biasing effect of the battery 175 upon the input electrodes of the push-pull amplifier tubes 177 and 179 is overcome. Under these conditions the oscillation frequencies generated in the oscillator 135, which have herein been assumed to be signals of a frequency of 97 kc., are then adapted to influence the push-pull tubes 177 and 179 so as to cause output currents from these push-pull connected tubes to appear in the primary winding 181 to which the plate potential source 183 is connected which are of a frequency of 97 kc.

50 These 97 kc. signals are then suitably transferred by way of the transformer secondary 185 to the input of the amplifier tube 187, which is energized from a battery or potential source 189, to be amplified and impressed upon the transformer primary 191 forming one primary section of the transformer having the output or secondary winding 133.

Thus, the signals from channels "A" and "B" which may be either telegraphic signals, picture modulated signals as produced from a photocell amplifier system, or even speech signals where desired and where the frequency separation of 5 the generated frequencies is suitable for sound work, are simultaneously impressed upon the secondary winding 133 of the transformer having the split primary 191, 131 and 229.

Simultaneous with this application of frequencies corresponding to periods of impression and interruption of the signals from channels "A" and "B" upon the transformer secondary winding 133 sound signals are also to be supplied thereupon to complete the multiplex arrangement. Such sound signals, it will be herein shown, are adapted to modulate the frequency stabilized oscillator 2, which generates a frequency herein-above assumed to be 100 ks., as was above pointed out. The generated frequencies at 100 kc. appearing in the tank or resonant circuit 41 of the oscillator tube 39 are impressed not only upon the transformer secondary 55 but also upon the transformer secondary 193 from which they are transferred to the amplifier tube 195, which is energized by a battery 197, so as to appear in amplified form in the transformer primary 199 connected in the output circuit of the tube 195. From the transformer winding 201 the 100 kc. energy is supplied to the input circuit 30 of an amplifier tube 203.

The sound signals which are assumed to be impressed upon the microphone 205 are transferred therefrom to the amplifier 207, which is suitably biased by way of a biasing source 209. The impressed sound signals thus control the amplitude of the plate current flowing in the output circuit of the tube 207, which circuit includes the inductance 211 and the plate current source 213, so that depending upon the sound signals supplied to the microphone 205 depends the voltage at the upper end of the inductance 211 which is supplied by way of a conductor 215 to modulate the output of the tube 203. The modulator tube 203 has connected in its output circuit a variable capacity element 217 and the transformer primary 219 which form together a resonant circuit 221. The modulation of the plate current in tube 203 is thus in accordance with the well known form of plate current modulation system.

The modulated 100 kc. voltage energy from tube 203 is then transferred by way of the inductance 219, forming the primary of a transformer, to the secondary winding 223 of this transformer to be suitably amplified in an amplifier 225 connected 55 by way of a conductor 227 to still another primary winding 229 of the transformer having as its secondary element the winding 133. The output circuit of tube 225 is then completed by way of a conductor 231 connected to the plate current 60 source 235.

If it is assumed that the sound modulation is no greater than 2500 cycles then it will be apparent that there appears in the secondary winding 133 of the transformer having the split primary 65 coils 191, 131 and 229 a series of signals which include the frequency band between 97.5 kc. and 102.5 kc. representative of the sound transmission and a 97 kc. tone as well as a 103 kc. tone representative of the telegraphic or picture signals. All 70 of these signals are then to be amplified by the linear amplifier system generally designated as 7, 12 and 13 of Fig. 1.

To produce a carrier frequency for transmission there is provided an oscillator unit 8 which 75

is of substantially standard and well known form. The oscillator or generator unit 8 includes an oscillation generation tube 237 having plate, grid and filament electrodes 239, 241 and 243, respectively, of which the plate electrode is connected to ground at 249 by way of a resonant circuit including the parallel combination of inductance and capacity 245, 247 which connects with the cathode or filament electrode of the tube by way of a plate current source 248. The tube grid electrode 241 is connected to ground through the series combination of a resistance 250 and inductance and capacity elements 253 and 259 all of which are connected in parallel with the piezo electric crystal frequency control element 263, so that the frequency generated by the oscillator tube 237 is stabilized by way of the crystal control element 263. To supply a suitable biasing potential to the tube 237 a biasing source may be connected with the grid electrode by way of the inductance 253 and resistance 250 at the terminal 255.

The generated frequencies of the oscillator tube 237 are then supplied to an amplifier tube 269 by way of a capacity coupling 267. The output circuit of the tube 269 comprises the primary winding 271 of a transformer and the plate current source 273 so that the amplified oscillation frequencies are supplied to the transformer secondary 275 from the plate inductance 271 and thereby caused to energize the input circuit of the frequency doubling stage comprising the tubes 277 and 279. The tube 277 and 279 are connected with their inputs in push-pull and supplied with current from the source 281 by way of the transformer primary 283. The currents flowing in the output circuit of tubes 277 and 279 cause proportionate voltages to be supplied to the secondary winding 285 of the output transformer. The secondary of this transformer connects by way of conductors 287, 289 and the center-tap conductor 291 to the input circuit of a second frequency doubling stage comprising the tubes 293 and 295 having their input circuits connected in push-pull and their output circuits in common so that the output energy at double the input frequency appears in the winding 297. This double frequency energy is then transferred by way of the secondary winding 299 to the tubes 303 and 305 which are suitably biased from the energy source 301 and signal energized also by way of the transformer secondary 333 so as to be modulated or controlled in accordance with the signals appearing in the signal input channels "A", "B", "C".

It is preferable to supply across each frequency doubler stage a tuning capacity, as shown, in order to tune the output system to the doubled frequency, but this is not absolutely essential and, where desired, the tuning capacities may be omitted.

The push-pull amplifier stage comprising the tubes 303 and 305 is, as shown above, supplied with energy at a frequency which is four times the generated carrier frequency. This push-pull stage is arranged as a carrier suppression stage. These tubes 303 and 305 are supplied with energy from a plate current source 309. The output circuit is tuned by way of the resonant combination of inductance 301 and capacity 308 to any desired frequency, for example, assume that oscillator 8 is set at 1500 kc. and with the twice doubling becomes 6000 kc. in transformer 297, 299. Then by modulation of the intermediate frequencies introduced into stage 7 in the secondary 133, 75 two side bands are produced. Then the output

circuit 307 and 308 is tuned to a frequency of 6100 kc. so that due to the modulation of the carrier frequency by the two telegraphic or picture signal inputs and/or the sound signal input there appears in the resonant circuit comprising 307 and capacity 308 signals of a frequency of 6097, 6100 as modulated by the 2500 cycle sound modulation and 6103 kc. provided, of course, that these are all passed by the 6100 kc. tuning and that the lower side band frequencies are suppressed due to the above suggested tuning selected. These signals at the above frequencies, which are assumed purely for the purpose of illustration and not in any sense with a view to limiting the scope of the invention since wide variations in selected frequencies may be made, are then again amplified in the linear amplifier stage. This amplifier is what has become known in the art as a class "A" amplifier and is ideally suited to the purpose of reducing any possible "cross talk" between the several channels of the system. The amplifier stage comprises the push-pull amplifiers 315 and 317 which have their input circuit suitably biased by the biasing source 313 and the input circuits suitably tuned to the selected frequency by way of a capacity element 312. Operating current is supplied from a source 319. The tubes 315 and 317 are supplied with controlling signals through the secondary winding 311 of the input transformer which has its end terminals connected to the tube input electrodes. The modulated signals appearing in the output circuit of the push-pull stage 315, 317, which output circuit comprises the resonant combination of inductance 321 and capacity 322, here again tuned to 6100 kc., still further selects the above-named frequencies with additional discrimination with respect to the lower side band frequencies. These frequencies, as amplified, are then supplied to the transformer secondary 323 to energize the push-pull tubes 327 and 329 by way of a tuned input circuit comprising the transformer secondary 323 and capacity 324, also tuned to 6100 kc. as in the previous stage. The amplifiers 327 and 329 are suitably biased by way of a biasing source 325 and receive their plate current from a source 331.

The output circuit of the push-pull stage 327, 329 includes the resonant circuit comprising the transformer primary 333 and the capacity 334 which is also tuned to 6100 kc. to discriminate against the lower side band frequencies produced from modulating the carrier frequency supplied to the push-pull stage 303, 305 by the sound and picture or telegraphic signals so that whatever signals now appear in the transformer primary 333 may be supplied to the secondary winding 335 of the transformer grounded at 337 so as to be radiated by the antenna 14 or by way of a suitable wire line connection to various receiving points.

The energy now transmitted from the antenna or any other suitable form of transmitting device 14 may then be received on a plurality of independent receiving instrumentalities comprising the antennae 350, 352, 354 from which the received signals are directed to the receivers 356, 358 and 360, respectively, which may be, where desired, the usual type of superheterodyne receivers tuned to suitable frequencies by means of a local oscillator. The output of the sound signal receiver 356 at 6100 kc. is then suitably amplified in an amplifier 362 and transferred through a low-pass filter 364 which is arranged to cut-off at 2500 cycles, which was above assumed to be the limit of modulation 7

by sound signals, and then passed to a sound reproducer 366.

The signals for telegraphic or picture signal transmission channel "A" are received in the receiver system 358 and the signals from transmission channel B are received in the receiver system 360. A local oscillator 368, generating for example a frequency of 6095 kc., may be used as the local oscillator for each receiver 358 and 360 so that there appears in the output of the receiver 358, which is tuned to the 6097 kc. signals, signals of a frequency of 2 kc. which are amplified in the amplifier 370. In the output of the receiver 360, tuned to a frequency of 6103 kc., there appears in the output, when the received frequencies are beat with the 6095 kc. frequency generated by the said local oscillator, signals of a frequency of 8 kc. which are suitably amplified in the amplifier 372. The signals from the amplifier 370 which are assumed to be at 2 kc. are then passed through the low-pass filter 374, which is also arranged to cut-off at 2500 cycles, and supplied to a recorder or the like 376. The signals appearing in the output of the amplifier 372 assumed to be of 8 kc. are then passed through a high-pass filter 378 arranged to pass all signals above 2500 cycles so that these signals may then be reproduced in a suitable recording and reproducing arrangement 380. Thus, it is seen that the sound signals and the picture or telegraphic signals are transmitted simultaneously and received simultaneously, that there is no interference produced between the sound and the telegraphic signals or between the separate telegraphic or separate sound signals and that it is possible to transmit simultaneously three separate and distinct messages.

In accordance with the arrangement herein shown it is, of course, obvious that many changes and departures may be made from the particular arrangement disclosed herein without departing from the spirit and scope of the invention and that it is possible not only to utilize two telegraphic or picture transmission channels and one sound transmission channel but any number of sound and picture transmission channels without departing from the spirit and scope of this invention, it being understood, of course, that the primary requirement is to determine whether or not there is sufficient separation between the locally produced tone frequencies to prevent overlapping of the independently produced signals.

It is to be noted that to furnish one example of an operative system utilizing the invention hereinabove described three channels have been chosen for illustrative purposes. It should be understood, however, that any number of side channels could be used without departing from the spirit and scope of this invention. Such number of channels might be 5, 7, 9 or more or less, it being understood that the number of channels can be widely varied. To illustrate an example for 5 channels in the system the modifications which would be required from the arrangement shown by Fig. 1, which for the most part would amount to mere duplication of parts, would involve the inclusion of five separate and distinct input circuits like those shown as "A", "B" and "C". Such a system would also require one master oscillator for producing the carrier frequency, a master oscillator for producing intermediate frequencies, and two audio frequency oscillators to obtain, when these generated frequencies beat with the frequencies generated by

the intermediate frequency oscillator, four separate and distinct side band frequencies, as has been disclosed by Fig. 1. There would also be other oscillators which are locked in step by the side band frequencies. For a system using five channels there would be four such oscillators and there would be means similar to those disclosed by Fig. 1 cooperating with and associated with each input circuit to key each of the four oscillators. The outputs from all of these oscillators would then feed the input circuit 133 which by following the arrangement of Fig. 1 might be five separate and distinct primary windings. In like manner a greater number of channels could be used.

A receiver device capable of operating with five channels would be substantially the same as shown by Fig. 2 but preferably would include an additional oscillator similar to the oscillator 368 and arranged similarly with two additional receiving circuits. From this illustration it is believed that it will be obvious that the system is extremely flexible and that with little difficulty it can be adapted to the inclusion of a great number of separate and distinct signalling channels.

This system also finds great application in diversity transmission in both telephone, telegraph and other types of message or intelligence communication. To illustrate one example for 30 telephony the telephone signal, for example in the three channel system first described, would be applied to the two outside channels but usually not to the center channel. So arranged the telephone signal would be amplified and then applied in opposite phase to two separate modulators coordinated with the outside channels. By this arrangement the same signal is applied oppositely across the grid cathode circuit of the two modulators, that is, the grids of the two 40 separate modulators are carried oppositely at each instant. In this manner the modulation in each channel is opposite, that is, one channel is "modulated up" and the other is "modulated down" and the output from both is maintained 45 at a constant level with a result that the depth of modulation can be a maximum for both channels without overloading or causing distortion of the transmission. This maximum can be the same as if only one channel were being used at 50 maximum power.

From this it follows that at the receiving points the advantages of diversity reception as taught by H. H. Beverage and H. O. Peterson is obtainable since the same signal appears on 55 each of two separate carrier frequencies. Other modifications of this general nature naturally follow from what has herein been described.

Of course, many other and varied modifications may be made without departing from the spirit 60 and scope of this invention and I believe myself to be entitled to make and use any and all of these modifications providing they fall fairly within the spirit and scope of the above disclosure and the hereinafter appended claims. 65

Having now described my invention, what I claim and desire to secure by Letters Patent is the following:

1. In a multiplex transmission system the method which comprises generating a plurality 70 of carriers of intermediate frequency, producing from the generated carrier frequencies side band frequencies corresponding to the upper and lower side band produced, producing intermediate frequency carrier energy stabilized by the produced 75

side band frequencies modulating each produced side band stabilized frequency and at least one generated carrier frequency independently by signals representative of the intelligence to be communicated, generating a transmission carrier frequency, modulating the transmission carrier by each of the modulated intermediate carrier frequencies, suppressing one side band frequency produced by the modulation of the carrier frequency by each modulated intermediate carrier, amplifying the modulated transmission carrier frequency, tuning the amplifying system sharply to the selected side band frequency produced by modulation, and transmitting the modulated carrier frequency representative of the intelligence signals supplied to all channels of the multiplex system.

2. The method of multiplexing signals for transmission which comprises generating a plurality of intermediate frequencies of constant value, producing from the intermediate frequencies side band frequencies by modulating one by the other, generating frequencies corresponding substantially to the produced side band frequencies, locking the substantially constant generated frequencies independently by each of the produced side band frequencies, modulating one intermediate frequency generated and the controlled side band frequencies independently of each other to produce simultaneously a plurality of related signals representative of the intelligence to be communicated upon each channel of the multiplex system, generating a transmission carrier frequency, and modulating the transmission carrier by each of the modulated intermediate frequencies produced.

3. The method claimed in claim 2 comprising, in addition, suppressing one of the side bands produced by each modulated intermediate frequency modulating the transmission carrier frequency.

4. The method claimed in claim 2 comprising, in addition, linearly amplifying the modulated transmission carrier frequency prior to transmission so as to avoid interference between the signals in each independent signal channel of the multiplex system.

5. In a multiplex signal transmitting system, a plurality of signal energized circuits each responsive to impressed intelligence signals, a plurality of stable generators of intermediate frequency, a plurality of unstable generators of in-

termediate frequency, means controlled by the stable generators to stabilize the unstable generators to maintain fixed frequency spacing and relationship between each generated frequency, means for modulating each controlled intermediate frequency source by the signals of a coordinated signal energized circuit, and means to control the transmission of energy simultaneously by the modulated intermediate frequency signals representative of all signal energized channels.

6. A signalling system comprising a source of carrier frequency energy, a constant frequency generator of intermediate frequencies, a constant frequency generator of low frequencies, means to produce by the combined output of both generators intermediate frequency side band frequencies, means to generate intermediate frequencies corresponding in value to the side band frequencies, means to stabilize the last named frequency sources by the produced side band frequencies, a plurality of independent signal controlled input circuits, means to modulate each intermediate frequency corresponding to the side band frequency and the intermediate frequency carrier independently of each other by the signals appearing in a single coordinated signal controlled input circuit, and means to modulate the carrier frequency for transmission by each of the modulated intermediate frequencies.

7. A multiplex system comprising a plurality of sources of intermediate frequency, a plurality of signal controlled circuits independently connected with each intermediate frequency source to modulate each independently of the other in accordance with the signals applied thereto, a low frequency source, means to produce from one high frequency source and the low frequency source side band frequencies to lock the remaining intermediate frequency sources at the produced side band frequencies, a source of carrier frequency energy, means to modulate the produced carrier frequency by each modulated side band frequency and one modulated intermediate frequency, means to suppress the side band frequencies produced on one side of the carrier frequency by modulation, and means to amplify linearly all the modulated frequencies to prevent interference in reception between the signals of each independent signal energized input.
